UNITED STATES PATENT OFFICE.

LEONARD A. YOUNG, OF HIGHLAND PARK, MICHIGAN.

SEAT-SPRING.

1,206,073.

Specification of Letters Patent. Patented Nov. 28, 1916.

Application filed February 25, 1916. Serial No. 80,499.

To all whom it may concern:

Be it known that I, LEONARD A. YOUNG, a citizen of the United States, residing at Highland Park, county of Wayne, State of Michigan, have invented a certain new and useful Improvement in Seat-Springs, and declare the following to be a full, clear, and exact description of the same, such as will enable others skilled in the art to which it pertains to make and use the same, reference being had to the accompanying drawings, which form a part of this specification.

This invention relates to seat springs, whether used for the seat proper or for the seat back.

The improved features comprise the use of a trussed double rim which makes a very strong margin for the seat spring; and a webbing provided with an elastic reinforcement. The webbing is of such a character that it provides a strong but yielding supporting surface over the top of the spiral springs. This supporting surface tends to eliminate the unevenness due to the tops of the spiral springs. This is very advantageous as it makes possible the upholstering of the springs with a much thinner layer of hair, thereby saving in this expensive padding. This webbing also absolutely prevents any of the hair dropping down between the spiral springs to interfere with their action and to initially require more hair for the cushion to take the place of that which in time sags down.

The character of the webbing with the elastic reinforcement and the character of the trussed ring will more fully appear in the specifications following.

In the drawings, Figure 1 is a top plan view of the cushion with the webbing on top of the springs, some of the parts being broken away to show the parts underneath. Fig. 2 is a cross section through the upholstered cushion. Fig. 3 is a sectional bottom plan view taken on the line A—A of Fig. 2, and being limited to one-half of the spring. This view omits the outer rim wire. Fig. 4 is a similar view with the outer rim wire and the webbing in place.

a designates the spiral springs, which are of the hour-glass type, although the exact form of the spiral is not material.

b designates the lower rim of *S* section, in which are pinched the bottom coils of the spiral springs and the bottom edge of the upholstering facing *c*. The springs are preferably tied together at the top by small links *d*.

The upper rim comprises a trussed double rim. The inner rim wire *e* is first assembled on the springs by securing it to the top coils of the spiral spring by clips *f*. This inner rim is provided with a plurality of offsets *g* forming, in connection with the outer rim, trusses very effective for the purpose of resisting side thrusts upon the rim.

The webbing *m* which forms the supporting surface above the spiral springs comprises a two layer fabric sewed together by parallel lines of stitches *h* forming pockets in which are contained flat zig-zag springs *i*. The fabric is preferably of a heavy grade of cheese-cloth. Preferably I employ two webbings, one (*m*) with the elastic reinforcement (the zig-zag wires) running in one direction, and the other (*n*) with the elastic reinforcement running in a direction at right angles to the direction of the zig-zag springs of the other webbing. Thus in Fig. 1 the pockets and zig-zag springs of the under webbing *m* run lengthwise of the spring and the pockets and zig-zag springs of the upper webbing *n* run crosswise of the seat spring. It will be apparent that by this arrangement there is not only a stronger supporting surface afforded but the zig-zag wires cross each other in such a fashion as to really make an intercrossed wire structure of small mesh so that there is practically no possibility of any of the hair sagging or tending to sag below the normal plane of the webbing. Not only is the hair properly held up but the zig-zag wires resting on top of the helical springs are of sufficient strength so that they practically eliminate any sensation of the tops of the spiral springs even when the spring is sat upon before the hair has been put in place. Especially does the webbing cause the spiral springs to lose their identity so

far as sensation is concerned when the two layers of webbing with intercrossed zig-zag runs are employed.

A convenient way of assembling the seat 5 spring is indicated in Figs. 3 and 4. The inner thrust rim wire is first assembled upon the spiral springs by banding the same to the top coils of the said spiral springs so that it can hinge with respect to the same.

- 10 The inner rim can also hinge on its connections to the top coil of the spiral springs. The webbing (both layers if two layers are used) is secured to the outer rim wire *j* before that rim wire is assembled on the seat 15 spring. This fastening of the webbing to the rim wire *j* is effected by the small band clips *k*. The outer rim wire and the webbing may then be laid over the tops of the spiral springs and the inner rim wire and 20 the band clips *l* pinched over the outer rim wire, the webbing and the offset portions of the inner trussed rim wire.

What I claim is:

1. In a spring construction, the combination of a plurality of springs, means upon 25 which the springs are carried, and a webbing for laying over the tops of the springs and provided with a reinforcement in the form of flat springs elastic in one direction 30 stretched over the tops of the springs.

2. In a spring construction, the combination of a plurality of spiral springs, means for carrying the same, and a pocketed fabric having flat extensible springs in the said 35 pockets, the said pocketed fabric being arranged over the tops of the spiral springs.

3. In a spring construction, the combination of a plurality of spiral springs, means for carrying the same, and a webbing comprising a fabric provided with pockets extending from one side of the spring construction to another, and having flat zig-zag 40 springs located in the said pockets.

4. In a spring construction, the combination of a plurality of spiral springs, means for carrying the same, and a webbing for stretching over the top of the springs, comprising a fabric sewed with parallel lines of stitching to form parallel extending 45 pockets and provided with zig-zag springs located in said pockets.

5. In a spring construction, the combination of a plurality of spiral springs, means for carrying the same, and a webbing for stretching over the tops of the spiral springs, comprising a two-layer fabric stitched to form pockets and provided with zig-zag springs contained in said pockets. 55

6. In a spring construction, the combination of a plurality of spiral springs, means for carrying the springs, and a webbing for the tops of the springs, comprising a two-layer fabric sewed together to form parallel pockets extending from one side to the other.

of the fabric and the completed spring construction and having flat zig-zag spring wires contained in said pockets and stretching from one side of the complete spring construction to the other.

7. In a seat spring construction, the combination of a plurality of spiral springs, means for carrying the springs, and a supporting fabric lying on top of the springs, comprising two layers of fabric sewed together with parallel lines of stitches forming parallel extending pockets running from side to side of the complete seat spring construction and having flat zig-zag springs, one contained in each pocket and extending from one side of the complete seat spring 75 construction to the other.

8. In a spring construction, the combination of a plurality of spiral springs, means for carrying the springs, and a supporting surface for drawing over the tops of the 85 spiral springs, comprising two webbings one of which is provided with an elastic reinforcement elastic in one direction only and the other of which is provided with an elastic reinforcement elastic only in a perpendicular direction to the direction of the elasticity of the reinforcement of the first-mentioned webbing.

9. In a spring construction, the combination of a plurality of spiral springs, means 95 for carrying the same, and a supporting surface for drawing over the top of the supporting springs, comprising two webbings each webbing comprising a fabric provided with pockets containing zig-zag springs, the 100 pockets and the zig-zag springs of one webbing extending in one direction and the pockets and zig-zag springs of the other webbing extending in a direction at right angles to the direction of the pockets and 105 the zig-zag springs of the first-mentioned webbing.

10. In a spring construction, the combination of a plurality of spiral springs, means for carrying the springs, and a supporting 110 surface for drawing over the tops of the springs, comprising a series of zig-zag springs extending from one side of the complete seat back spring to the other, and a second series of zig-zag springs superimposed on the first zig-zag springs and running angularly across the first series of zig-zag springs so as to present a crossed wire structure.

11. In a seat spring, the combination of a 120 plurality of spiral springs, and means for carrying the springs including a trussed double rim for the springs.

12. In a seat spring, the combination of a 125 plurality of spiral springs, and means for carrying the same, including a double wire trussed rim construction.

13. In a seat spring, the combination of a

plurality of spiral springs, and means for carrying the same, including a rim comprising an inner rim wire having offset portions forming trusses and an outer rim wire tied to the said inner rim wire at the trussed portions.

14. In a seat spring, the combination of a plurality of spiral springs, and means for

carrying the same, including a rim comprising an inner rim wire hinged to the spiral springs and having offset portions, and an outer rim wire hinged to the inner rim wire at the offset portions.

In testimony whereof, I sign this specification.

LEONARD A. YOUNG.
